UNITED STATES PATENT OFFICE.

ANTHONY VANDERVELD, OF GRAND RAPIDS, MICHIGAN, ASSIGNOR TO GRAND RAPIDS SHOW CASE COMPANY, OF GRAND RAPIDS, MICHIGAN, A CORPORATION OF MICHIGAN.

SECTIONAL STORE FURNITURE.

1,253,546.

Specification of Letters Patent. Patented Jan. 15, 1918.

Application filed January 8, 1915. Serial No. 1,191.

To all whom it may concern:

Be it known that I, ANTHONY VANDERVELD, a citizen of the United States of America, residing at Grand Rapids, in the 5 county of Kent and State of Michigan, have invented certain new and useful Improvements in Sectional Store Furniture; and I do hereby declare the following to be a full, clear, and exact description of the invention, such as will enable others skilled 10 in the art to which it appertains to make and use the same.

This invention relates to sectional furniture adapted to be used especially in equipping and furnishing stores. In furniture of this character a plurality of sections are placed in superposed relation to any desired height, the sections being of various designs to contain varied articles of merchandise. 15 It is customary to place these vertical series of sections end to end along the walls of stores or in any other place where they may be conveniently located and to space the adjacent ends a distance apart, facilitating 20 the ready removal of any section from any of the vertical series without disturbing sections of other vertical series which may be associated therewith. The space between the spaced apart ends of the sections is cov- 25 ered and the ends of the sections are tied together in substantially rigid relation by means of a post or pilaster extending from the top to the bottom of the vertical series of sections. My invention is concerned with 30 the provision of new and improved means and constructions to be used in covering the space between the ends of sections, in tying the sections together and in alining the sections so as to make the appearance and have 35 the effect of a solid built construction, at the same time permitting the ready removal of the post or pilaster and the interchanging of sections in the furniture equipment. The invention is disclosed in its preferred em- 40 bodiment in the accompanying drawings, in which;

Figure 1 is a perspective view with parts broken away showing two of the vertical series of sections secured together by the im- 45 proved construction.

Fig. 2 is a fragmentary sectional view taken on the line 2-2 of Fig. 4.

Fig. 3 is a fragmentary vertical section taken through one of the sections of the 55 series; and

Fig. 4 is a fragmentary horizontal section taken through the post or pilaster and the front portions of adjacent sections placed end to end.

Similar reference characters refer to similar parts throughout the several views of the drawings.

In the embodiment of the invention shown a plurality of sections adapted to contain various articles of merchandise are indicated at 1 as located in superposed relation to form a vertical series. The lowermost section rests on a base 2 and the uppermost section carries a top or cornice 3. A plurality of these vertical series of sections are placed end to end with the ends 4 of the sections spaced a distance apart. To tie the ends of all of the sections in adjoining vertical series together and to cover the space therebetween, a post or pilaster comprised of an outer strip 5 of a width sufficient to pass over the space between and a portion of the fronts of the ends 4 of the sections is used having attached thereto on its rear side a channel member 6, the flanges 7 of which extend rearwardly into the space between the adjacent ends of the sections and lie adjacent said ends. This post and channel are of a length equal to the distance from the floor to the top of the cornice 3. 85

The ends of each section are provided with openings 8 which are adapted to align with similar openings 9 formed in the flanges 7 of the said channel and each end 4 of each section is provided with a slot 10 on the inner side thereof as shown. U-shaped tie members 11 may be inserted through the openings 8 and 9, the legs thereof passing over adjacent portions of the flanges 7 and the end members 4, thereby tying said flanges and ends of sections rigidly together. The slot 10 is of sufficient depth that the legs of the tie members 11 on the inner side of the sections will be entirely concealed therein and will not offer any obstruction 100 to drawers or other similar articles of retaining members which may be located in the sections.

It will be evident from this construction that when a plurality of vertical sections are located in horizontal relation with the ends spaced apart and tied together in the manner described the appearance and effect of a solid construction will be obtained, but that by merely removing the ties 11 the post or pi- 110

laster may be removed from between the ends of any of the vertical series of sections. In this manner any of the vertical series may be rendered entirely independent of the others 5 and may be rearranged at will. The construction is simple and economical and one very practical in use and operation. The claims define the invention and all modifications falling within their scope are to be considered as comprehended within the invention.

I claim:—

1. In combination, a plurality of independent vertical series of superposed sections located in horizontal relation with the ends of adjacent sections spaced apart; a post or pilaster lying at the front of and covering the space between the adjacent ends of sections, said post or pilaster including 15 a channel having flanges lying adjacent the section ends, and tie members extending through said flanges and section ends for securing them together, said tie members being accessible from within the sections and 20 readily removable to permit disengagement of the sections and post or pilaster.
2. In combination, a plurality of independent series of superposed sections located end to end in horizontal relation with the 25 ends of the sections spaced apart, a post or pilaster located at the front of and covering the space between the adjacent ends of the sections, said post or pilaster including a channel member having rearwardly extend-

ing flanges lying adjacent the ends of the sections, and removable U-shaped tie members extending through said flanges and ends of the sections, with the legs of the tie members engaging the inner sides of the sections and flanges and accessible for ready removal from within the sections, substantially as described.

3. In combination, a plurality of independent vertical series of superposed sections located end to end in horizontal relation with the ends of adjacent sections spaced a short distance apart, a post or pilaster located at the front of and covering the space between the adjacent ends of the sections, said post or pilaster comprised of a channel member having a strip secured to the web thereof of greater width than the web, the flanges of the channel extending rearwardly into the space between the ends of the sections, and removable U-shaped tie members 50 extending through said flanges and ends of the sections with the legs of the tie members engaging against the inner sides of the flanges and ends of the sections, said legs engaging against the inner sides of the section ends lying in slots therein but accessible for ready removal, substantially as described. 55

In testimony whereof I affix my signature in presence of two witnesses.

ANTHONY VANDERVELD.
